COMBINATION CHAIR

Oland Townsend, Newburgh, N. Y.

Application April 20, 1934, Serial No. 721,594

1 Claim. (Cl. 155—170)

This invention appertains to new and useful improvements in furniture, and more particularly to a novel chair having accommodations thereon for divers purposes.

5 The principal object of the present invention is to provide a chair wherein various features of comfort and storage accommodations are available without the occupant leaving his seat.

Other objects and advantages of the invention 10 will become apparent to the reader of the following specification.

In the drawings:—

Figure 1 represents a top plan view of the 15 chair, partly broken away and showing several of the storage chambers in extended position.

Figure 2 represents a front elevational view of the chair, with certain of the storage chambers in extended position.

Figure 3 represents a side elevational view of 20 the chair.

Figure 4 represents a vertical sectional view taken substantially on line 4—4 of Figure 1.

Figure 5 represents a fragmentary detailed 25 section view of the latch for the shoe container.

Referring to the drawings wherein like numerals designate like parts, it can be seen that the chair consists of the seat 5, the back 6, the front legs 7 and the rear legs 8, as well as an 30 elevated arm rest 9.

Hingedly mounted within the space between each of the arm rests 9 and the seat 5 is a horizontally swingable box 10 for accommodating stockings and various other articles of apparel.

35 A substantially triangular shaped tray 11 is hingedly connected, as at 12, to one of the front legs 7, and this tray is swingable to a position under the seat 5. Numeral 13 represents the front wall of this tray 11 and at its free end is 40 provided with a keeper 14. The front wall 13, at its inner side, is provided with a wire rack 15, while upon the floor of the tray 11 is an inclined shelf 16. In some instances, high heel shoes can be hung with their heels over the rack 45 15, while the sole portions rest upon the shelf 16, while in the case of low heel shoes, the heels can be engaged over the upper edge of the shelf 16, while their sole portions can rest upon the rail 17.

50 The lower ends of the front and rear legs 7—8 are connected by base bars 18, each of which is provided with a slot 19 therein for slidably receiving the cross bar 20. This cross bar extends through the elongated members 55 21—21 which are pivotally connected, as at 22, to the intermediate portions of the bars 23—24

which at their outer ends hingedly connect, as at 25, to the inclined foot rest board 26 which is supported by legs 27 pivotally connected at their upper ends, as at 28, to the upper end of the foot rest board 26. The inner ends of the members 23—24 are hingedly connected, as at 29, to the base bar 30 connecting the front legs 7 of the chair. 5

Obviously, when it is desired to collapse the 10 foot rest, the board 26 can be swung over and upon the members 23—24, while the legs 27 will rest upon the board 26 and by swinging the members 23—24, this collapsed assembly can be 15 swung in to rest upon the cross bar 20 as the latter slides along the slot.

The front leg 7 other than the leg to which the tray 11 is hingedly connected, has a recess 31 at the inner side thereof and a bore 32 extending from the front side of the post through to meet the recess 31. An anchor plate 33 is 20 located in the leg between the recess 31 and the bore 32 and has an opening therein through which the push pin 34 is slidably. This pin is provided with a ball 35 at its inner end which seats in a socket in the swingable catch 36, the catch being pivotally connected at one corner, as at 37, to the anchor plate 33. The catch 36 is provided with a recess 38 for receiving the keeper 14 on the tray 11 when the tray is 25 disposed in a closed or out-of-use position. 30

Obviously, with a spring 39 normally keeping the catch 36 engaged with the keeper 14, a push on the pin 34 will readily overcome the tension of this spring and cause the catch 36 to swing 35 so that the tray can readily be pulled out to the exposed position shown in Figure 1.

While the foregoing specification sets forth the invention in specific terms, it is to be understood that numerous changes in the shape, size and materials may be resorted to without departing from the spirit and scope of the invention as claimed hereinafter. 40

Having described the invention, what is claimed as new is:

A chair structure comprising a seat having 45 supporting legs, front and side base members connecting the front legs at the lower ends thereof, and the front legs with the rear legs at the lower ends thereof, said side base members being provided with grooves on their opposed sides, a slide rod having its ends slidably disposed in said grooves, a foot rest hingedly connected to the front base member, and a link member pivoted to the foot rest and connected to said rod. 50

OLAND TOWNSEND. 55
